INSULATOR

Arthur O. Austin, near Barberton, Ohio, assignor, by mesne assignments, to The Ohio Brass Company, Mansfield, Ohio, a corporation of New Jersey

Application September 30, 1931, Serial No. 565,944.

9 Claims. (Cl. 173—318)

This invention relates to insulators rigidly connected together in series to form posts or stacks, and has for one of its objects the provision of connecting means for such insulators which will be economical to manufacture, easy to install, and efficient in operation.

A further object is to provide connecting means for insulators which will permit easy removal of a unit in a connected series.

10. Other objects and advantages will appear from the following description.

The invention is exemplified by the combination and arrangement of parts shown in the accompanying drawing and described in the following specification and it is more particularly pointed out in the appended claims.

In the drawing:

Fig. 1 is a vertical sectional view of an insulator having one embodiment of the present invention applied thereto.

Fig. 2 is a section taken at right angles to Fig. 1.

Fig. 3 is a view similar to Fig. 2 showing a modification.

Fig. 4 is an end view and Fig. 5 is a plan view 25 of a key for holding the two parts of the insulator together.

In rigidly connected insulators more particularly those used for disconnecting switches or supporting bushings, it is desirable to make the insulators up in sections so that they may be readily assembled or disassembled and so that the loss of a part will not necessitate the loss of the other members. While it is comparatively easy to bolt the metal parts attached to the insulators together, considerable difficulty is encountered in providing a strong mechanical connection at low cost and one which does not materially impair the electrical properties of the insulator by reducing the flashover voltage due to the projection 40 of corners or parts.

In my improved connection, means are provided for forming an efficient joint or connection both electrically and mechanically. Fig. 1 shows an insulator having dielectric members 10 and 11 to which a cap 12 and a pin 13 are attached by cement or other suitable means. The pin is preferably provided with a base flange or an enlargement 14, arranged for connection with the cap of an adjacent insulator in a stack, as shown at 50 the top of the figure. Where several insulators are mounted together, it is necessary to provide a strong mechanical joint between the flange 14 and the top of the cap 12.

In the form shown in Figs. 1 and 2, this is accomplished by using a key 15 fitting in dovetail

slots 16 and 17 in the cap 12 and base 14 respectively. The key 15 locks the two parts together. This key is preferably constructed to permit of some tolerance or irregularity in the connected parts and, at the same time, develop the necessary pressure between the base 14 and top of the cap 12 to insure rigidity. In general, the key can be used to hold the parts together both for bending and torsional moments. If desired, additional keys or pins 18 may be used for insuring tightness. The main key 15 may be shoved into position and if the keys 18 are slightly larger than the vertical space provided for them, they may be forced into position, tending to increase the locking effect of the key 15. The keys 18 preferably have a slight taper when used for this purpose or have a chamfered end so that they may be forced into position. The key member 15 may be made in a number of different forms. One method of construction is to make this member out of sheet metal strips having slits in the edges forming tongues, alternate ones of which are bent upward and downward respectively so that one pair will come into contact with the slot in the cap, and the adjacent pair come in contact with the slot in the connected base. This method makes it possible to provide sufficient resiliency to overcome irregularities and, at the same time, insures adequate pressure between the parts.

In order to assemble two parts together, the key is forced through the slots by any convenient means such as a small hydraulic press or a screw member similar to a seat clamp. It is evident that if it is desired to disassemble the insulators at any time, this may be readily carried out by forcing the key member out of the slot, thus making it possible to assemble the desired number of units. Very careful alignment may be provided either by the key member or by additional pins 18 or dowels 20, as shown in Fig. 3.

Where a single key only is used, the base and cap are not necessarily located definitely relative to each other in a direction in line with the slot. This location is determined by the keys or pins 18 or dowels 20.

Where slight clearance is provided as shown in Fig. 3, the keys may be given a waving form, as shown somewhat exaggerated in Figs. 4 and 5. Where a waved type of key is used, it preferably does not bear on the cap and pin base at points which are directly opposite but rather at points which are displaced relatively of each other longitudinally of the key. By limiting the stiffness of the key, it is possible to provide for considerable latitude in fabrication as the key will simply

bend to accommodate any difference in depth of the key way. This may be accomplished by a waved type of key in which there is a certain amount of resiliency or the result may be accomplished in a key which simply accommodates itself by exceeding the elastic limit distorting to accommodate any differences where necessary.

I claim:

1. An insulator comprising dielectric members having fittings secured thereto for connecting said dielectric members together in a stack, adjacent fittings in a stack having contacting faces and registering dovetail grooves in said faces, and a key having resilient diverging portions adapted to fit the registering dovetail grooves to hold said fittings together.
2. An insulator comprising dielectric members having fittings secured thereto, and means for locking the fittings of different dielectric members together to hold said dielectric members in stack formation, said means comprising a key having oppositely extended resilient tongues adapted to engage dovetail slots in adjacent fittings to draw said fittings together and hold them in position.
3. An insulator stack comprising a plurality of dielectric units each provided with a base and a cap, the cap and base of adjacent units being in engagement, and means for locking an engaging cap and base together comprising registering slots in said cap and base, a key for entering said slots to lock said cap and base together, and means for exerting a separating force on a connected cap and base to tighten said key in said slots.
4. An insulator comprising a pair of dielectric members having fittings secured thereto, said fittings having contacting faces and registering grooves in said faces, said grooves having enlarged inner portions, and a key having enlarged heads for entering enlarged portions of said grooves, said heads having bearing points spaced from one another in the direction of the axis of the key to provide yielding connection with the faces of said grooves.
5. A key for securing together adjacent elements, said key being formed of a strip of sheet

metal having the edges thereof slit to form tongues, alternate tongues being bent in opposite directions transverse to the plane of the strip and adapted to engage inclined faces of registering grooves in adjacent elements to hold said elements together.

6. The combination with contacting elements having registering dovetail grooves, of a key comprising a strip of sheet metal having diverging tongues extending from opposite edges thereof and inclined in opposite directions from the plane of said strip and disposed in said grooves and yieldingly engaging the inclined faces of said dovetail grooves to hold said elements together.

7. An insulator comprising a pair of connected units with fittings having engaging faces and registering grooves in said faces, said grooves being undercut to provide holding faces and a key disposed in said grooves and having yielding projections bearing upon the holding faces of said grooves at spaced points only, the bearing points on the face of one fitting being offset relative to the bearing points on the face of the connected fitting.

8. An insulator comprising a plurality of units, said units having openings forming a key-way with complementary bearing faces on said respective units, a key in said key-way and engaging said bearing faces at spaced intervals thereon for resiliently holding said units together, the points of engagement of said key with the bearing face of one of said units being staggered relative to the points of engagement with the bearing face of the other of said units, and additional means for preventing relative movement of said units in the direction of the axis of said key.

9. The combination with a pair of elements having abutting faces and registering dovetail grooves in said faces, of a key having resilient tongues disposed at opposite sides thereof and engaging the faces of said grooves for holding said fittings together, and wedging means acting to separate said fittings to place said tongues under resilient stress.

ARTHUR O. AUSTIN.
